UNITED STATES PATENT OFFICE.

LOUIS BARON, OF NEW YORK, N. Y.

COMBINED TABLE AND IRONING-BOARD.

1,160,126.

Specification of Letters Patent. Patented Nov. 16, 1915.

Application filed August 3, 1915. Serial No. 43,421.

To all whom it may concern:

Be it known that I, LOUIS BARON, a resident of the city of New York, in the county of New York and State of New York, have 5 invented certain new and useful Combined Tables and Ironing-Boards, of which the following is a specification.

This invention relates to ironing machines, and its principal object is to provide 10 a simple, inexpensive, strong, conveniently operated, reliable, and improved table and ironing board, whereof the table is at an elevation suitable for various ordinary purposes, and the ironing board of which may 15 be raised to an elevation suitable for ironing and may be lowered or restored in inoperative state.

Other objects and advantages will hereinafter appear.

20 In the accompanying drawings, Figure 1 is a general front elevation of the table and ironing board, showing the latter extended and elevated in position for ironing. Fig. 2 is a front elevation showing the ironing board lowered and restored to inoperative state. Fig. 3 is a sectional end elevation of the table and ironing board, taken on the line $x-x$ of Fig. 1.

The table comprises a table-top 1 joined 30 to a supporting framework 2 which is mounted upon legs 3. Underneath the table-top 1 and transversely thereto are located two bars 4 which are disposed parallel to each other. Each of said bars has a portion 5 bent rightangularly thereto and at its extremity 6 is pivotally connected to an ironing board 7. Said bars are mounted in guides in which they may be turned about their axes and through which they may be 35 also slid longitudinally in a direction toward and away from the front 9 of the table. The ironing board 7 comprises a central portion 7^a, to which the bar-portions 5 are directly pivoted, and at the extremities 40 of said central portion are connected board-portions 7^b by means of hinges 10, whereby the end-portions 7^b of the ironing board are adapted to be swung upwardly about hinges 10, in the direction of the arrows, and to be 45 folded over to lie on top of the central portion 7^a.

When in inoperative state the end-portions 7^b of the ironing board 7 are folded over upon the central portion 7^a thereof, 50 Fig. 2 and said board is in this folded state retained underneath the folded table-top 1.

and inside the table-frame whereinto it has been slid, together with its supporting bars 4. In this position the folded ironing board rests upon a ledge 11 of an opening 12 provided in table-frame 2, and the bar-portions 5 are disposed approximately horizontally, as shown by the dotted lines in Fig. 2. When it is desired to utilize the ironing board 7 it is first withdrawn from concealed 60 position underneath the table-top 1 and its end-portions 7^b are unfolded about their hinges 10, and then the board is raised above the table-top 1, to an elevation suitable for ironing, by swinging it together 65 with the bar-portions 5 a quarter turn in a clockwise direction about their guiding hinges 8. The board thus rising in parallelism with the table-top 1 is disposed parallel thereto and horizontally when in elevated 70 position and its supporting bar-portions 5 are disposed in vertical position. Locking bars 13, hinged to the corners of the table-top 1 at 14 and having slotted extremities 15, may be then swung upwardly about 75 their hinges and their slots caused to engage pins 16 secured to the rear edge of the board 7, whereby the ironing board is firmly locked and maintained in elevated state, and the ironing therewith may be thereupon 80 proceeded with conveniently.

In order to restore the ironing board to its inoperative state and dispose it out of the way, it merely requires unlocking of the bars 13, folding up of the board-portions 90 7^b, and then swinging of the board with its supporting bar-portions 5 in an anti-clockwise direction to aline it with the opening 12 and sliding it inwardly underneath the table-top 1 in concealed state. A stopping projection 17 at the extremity of each bar 4 abutting against the rear guide 8 limits the outward longitudinal movement of the bars 4 and the outward extension of the board 7, while abutment of said projection against the rear bar 18 of frame 2 limits the inward movement of bars 4 and the inward sliding of the board 7.

The table-top 1 may be that of a sewing 105 table or any other table for domestic purposes. As here shown the table-top is at an elevation suitable for dining or doing useful work about a kitchen or similar place, and the board 7 is elevated above the top of the table to an elevation which is most convenient for doing ironing work. While the ironing board is being utilized the table-top 110

may be conveniently used for placing garments and goods to be ironed thereupon, and also in other ways in conjunction with the ironing. Underneath the folded board 7 and within the table-frame 2 is built in an ice-box 18, and adjacent said box are built in a bread box 19, a drawer 20 for kitchen articles, and a sliding board 21 which may be withdrawn and extended so as to be used for chopping articles of food thereupon.

Variations may be resorted to within the scope of the invention.

Having thus described my invention, I claim:

1. The combination of a table, an ironing board adaptable to slide thereunder and to be extended outwardly therefrom, and means to elevate said board to an ironing elevation above said table.
2. The combination of a fixed table, an ironing board, said board adaptable to be folded up, means to slide said board in folded state under and to extend it outwardly from said table in lateral directions, and means to elevate said board to an ironing elevation above said table.
3. The combination of a fixed table, an

ironing board, means to maintain said board concealed under said table and to elevate said board to an ironing elevation above said table, and means to fold up said board when in inoperative state and to unfold it when at an ironing elevation.

4. The combination of a table, an ironing board hinged thereto, means to slide said board under said table and to extend it outwardly therefrom, means to swing said board about its hinges to raise it to an ironing elevation above said table, and means to maintain said board in elevated state.

5. The combination of a table, an ironing board, means to slide said board under said table and to extend it outwardly therefrom, and supports hinged to said board and to said table to swing said board to an ironing elevation above said table.

Signed at the city of New York, in the county of New York, and State of New York, this 30th day of July, A. D. 1915.

LOUIS BARON.
